Primary Examiner—Jeffrey Asch[57] **CLAIM**

The ornamental design for a combined cordless hand phone and charger, as shown and described.

DESCRIPTION

FIG. 1 is a front elevational view of a combined cordless hand phone and charger showing the new design;

FIG. 2 is a rear elevational view of the hand phone of FIG. 1;

FIG. 3 is a top plan view of the hand phone of FIG. 1;

FIG. 4 is a bottom plan view of the hand phone of FIG. 1;

FIG. 5 is a left side elevational view of the hand phone of FIG. 1;

FIG. 6 is a right side elevational view of the hand phone of FIG. 1;

FIG. 7 is a perspective view of the hand phone of FIG. 1;

FIG. 8 is a front elevational view of a charger of the combined cordless hand phone and charger showing the new design;

FIG. 9 is a rear elevational view of the charger of FIG. 8;

FIG. 10 is a top plan view of the charger of FIG. 8;

FIG. 11 is a bottom plan view of the charger of FIG. 8;

FIG. 12 is a left side elevational view of the charger of FIG. 8;

FIG. 13 is a right side elevational view of the charger of FIG. 8;

FIG. 14 is a perspective view of the charger of FIG. 8; and, FIG. 15 is a perspective view of a combination of the hand phone of FIG. 1 and the charger of FIG. 8.

The hand phone and charger have been shown separately in FIGS. 1-14 for convenience of illustration.
